B. THOMAS.
APPARATUS FOR THE OXIDATION OF ATMOSPHERIC NITROGEN.
APPLICATION FILED APR. 27, 1920.
1,437,569. Patented Dec. 5, 1922.

INVENTOR
B. Thomas.

UNITED STATES PATENT OFFICE.

BRUNO THOMAS, OF SEATTLE, WASHINGTON.

APPARATUS FOR THE OXIDATION OF ATMOSPHERIC NITROGEN.

Application filed April 27, 1920. Serial No. 377,138.

To all whom it may concern:

Be it known that I, BRUNO THOMAS, a citizen of the United States, residing in Seattle, Washington, have invented new and useful

5 Improvements in Apparatus for the Oxidation of Atmospheric Nitrogen or for Other Purposes, of which invention following is a specification.

The invention relates to an apparatus employed in the formation of electrical arcs, which arcs are used for the electrical treatment of gases, as per example for the fixation of atmospheric nitrogen.

10 The object of my invention is to provide a combination of electrodes, so arranged, that the electrical arc will be more efficient in its action upon the gases.

In the accompanying drawing, I have shown some diagrams which will illustrate 20 the new feature of my invention—without thereby limiting my claim to such features which are not essential to carry out my invention.

Fig. I^a shows a section, and Fig. I^b a plan 25 of such an apparatus for illustration purposes. They consist of a chamber (1) with a tangentially located air inlet (2), and an outlet opening (3). This outlet opening constitutes an annular electrode. Another 30 electrode, named the center electrode, is located along the axis through the center of the annular electrode. When a suitable electric current is passed through, a spark will 35 spring from the center electrode to the edge of the annular electrode, as marked by $x-x$. This spark will be substituted by an arc. The heat of the arc will create a draft upwards through the annular electrode and the arc will bend up against the orifice and 40 spreading out almost fill the opening. At the same time, the air sucked in through the tangential inlet (2) will rotate in the chamber and out of the opening and thereby move the upper end of the arc slowly around the

45 edge of the opening, constantly shifting the attacking point. As the gases are cooled immediately, having passed through the arc—gases of comparatively high concentration will be produced in this manner. However, 50 a higher efficiency in oxidation, as relating to the consumption of energy, will be obtained if the air current is given more velocity—either by increased draft, or pressed in through the inlet.

55 The former way seems preferable. In either case, the gases passing through the

orifice will adopt a centrifugal movement, increasing with the velocity. Such a movement will be beneficiary in several ways. It will create a low pressure in the center of the movement, and thereby form a core of the lower end of arc, around which the gases will circulate—and it will create a higher pressure around the edge of the orifice, thereby increasing the resistance in the arc as follows: increase the amount of energy or capacity of the apparatus; and further, an intensified rotation will split the upper end of the arc into sparks and intensify the immediate cooling of the reacting gases. These effects may be observed also if the center electrode is placed outside the intake chamber, as shown in Fig. II. By a high velocity of the gases and following rapid rotation, the core of the arc will stay downward through the center of the opening and a ring of sparks will spring from the core out to the annular electrode. If the movement is further increased, and the bottom of the chamber is a metal plate connected with the annular electrode, the core of the arc will go right down to the bottom, while at the same time the ring of sparks may be observed around the edges of the orifice—as shown in Fig. IV.

Fig. III shows a hollow center electrode which may be used for admission of other gases, if wanted, and also to cause a shifting of the attacking point of the electric arc.

Fig. V shows a combination of two orifices placed opposite each other, each provided with a center electrode between which electrodes the arc is started, and by the centrifugal movement drawn out to a ring form.

It is preferable that more than one tangential inlet to the air chamber is applied—in order to give the rotating movement a more proper and correct form.

I claim:

1. An apparatus for electrical treatment of gases, comprising an orifice constituting an annular electrode in combination with a center electrode located along the axis through the center of the annular electrode, and means to give the gases a rotating movement around the axis.

2. An apparatus for electrical treatment of gases comprising an orifice constituting an annular electrode in combination with a center electrode terminating inside the plan

of the orifice and means to give the gases a rotating movement around the axis mutual for both electrodes.

3. An apparatus for electrical treatment of gases, comprising an orifice constituting an annular electrode in combination with a center electrode, terminating outside the plan of the orifice and means to give the gases a rotating movement around the axis mutual for both electrodes.

4. An apparatus for electrical treatment of gases, comprising an orifice constituting an annular electrode in combination with a tube-formed center electrode, and means to give the gases a rotating movement around the axis mutual for both electrodes.

5. An apparatus for electrical treatment of gases comprising an orifice constituting an annular electrode in combination with a center electrode located on the axis of the annular electrode, and means to drive a rotating air current through the annular electrode.

6. An apparatus for electrical treatment of gases, comprising an annular electrode located in a gas outlet from and around the axis of a round chamber into which chamber the gases to be treated enter tangentially and by a second electrode located on the axis of said chamber.

B. THOMAS.
